UNITED STATES PATENT OFFICE.

CHARLES H. HANAWALT, OF BURBANK, CALIFORNIA.

ADJUSTABLE FIREPLACE SUPER-FIRE BACK.

Application filed November 28, 1927. Serial No. 236,170.

This invention relates to fire place structures and especially to a super heating means for heating air in a closed back chamber having air inlet means and air outlet means which latter leads to a discharge register in any desired location, near or remote as to the fireplace.

An object is to provide a super-heater for utilizing much of the heat that is lost by absorption into the usual fire-brick backs and to provide a sectional back which can be adjustably assembled in fire-place recesses of various widths.

Another object is to provide a fire back structure which will not in any way choke up the fire flue at the rim of the fire back, and an object is to so construct the fire back as to obtain an effective draft.

An important object is to provide a fire back which is composed of separate side wall and back panels of substantial material which may be made at low cost and assembled when set in place without requirement of expert help and which is free of complex and numerous lines of joint.

There are other objects, advantages and features of construction, combination and details of means as will be made manifest in the following specification of the herewith illustrative embodiment; it being understood that modifications, variations and adaptations may be resorted to within the spirit, scope and principle of the invention as it is more directly claimed hereinafter.

Figure 1 is a perspective of the fire-back.

Figure 2 is a vertical section of a chimney and fire-place structure.

Figure 3 is a plan of the decking bed and its platform.

Figure 4 is a detail section of a joined wing and panel parts.

Figure 5 is a plan of the set up panel and side wings, and applied deck rods.

The fire box consists of a main back panel 2 of cast-iron having a lower vertical portion and a forwardly inclined upper heat deflecting part. The rear face of the panel has vertical and transverse, intersecting stiffening ribs 3-4.

Along the top, rear margin of the panel 2 is a shelf 5 and the bottom edge has a sealing web 6 adjacent to the floor of the fire-place. The panel 2 is plane or flat transversely from edge to edge.

To complete a fire box in front of the panel 2 I provide right and left hand side wings

7-8 having vertical front edges 9 with sealing webs 10 and with rear abutment flanges 11 whose faces conform to the angled front face of the panel 2.

Since fire-places are not of uniform width my present invention provides for the adjustment or setting or attaching of the wings 7-8 to different positions against the panel as necessary according to the width of the opening. Hence the wings are bolted at 12 to the face of the panel 2.

The wings 7-8 are ribbed on the back and have top shelves 13.

When the wings and the panel have been set and bolted in the recess an air chamber C is formed at the rear of them and this is closed at the top by a deck, which is supported by stiff rods 15 having rear ends sunk in the brick work B and front ends resting on the shelves 5-13. On these rods is laid a sheet metal plate 16 upon which is tamped a bed of cement 17 which effectually seals the top of the air chamber and provides a clear top or throat T for the chimney A.

The footing and the meeting edges of the panel 2 and the wings 7-8 are well sealed in plaster to keep out fire gases and fresh air is let into the chamber C by conduit 20 and out of the chamber by conduit 21 to any place of discharge desired.

What is claimed is:

1. A sectional air heater structure in combination with a fireplace and chimney throat including a forwardly pitched back panel and side wall wings abutted against and secured to the front of the panel, a fireplace back wall, and a decking structure supported by the panel and wings and back wall; said panel and wings having shelves and rods resting thereon and in the fireplace wall and said decking including a sheet metal plate laid on the rods and a cement bed on the sheet metal plate.

2. A fireplace structure comprising, in combination, a chimney structure forming a recess and its smoke throat outlet, an inner fire wall consisting of a metal back and attached side wings spaced from the recess back and sides to form a hot air chamber, said wings contacting with the side walls at the front to close the front of the chamber; and a top structure supported by the tops of the inner fire back wall and having supporting rods resting in the chimney wall at the sides and back of the recess.

3. A sectional air heater structure in com-

bination with a fire place and chimney throat including a back panel which is plane transversely from edge to edge and side wall wings having flanged rear, vertical edges complementary to the vertical contour of the back and fixedly secured to the ends of the back at distances thereon determined by the width

of a given fire place in which the heater is to be mounted, and means forming a sealing top closure for a hot air chamber formed between the heater and the back wall of the fire place. 10
